UNITED STATES PATENT OFFICE.

CLARENCE E. SMITH, OF NEW BRITAIN, CONNECTICUT, ASSIGNOR TO
NORTH & JUDD MANUFACTURING COMPANY, OF NEW BRITAIN,
CONNECTICUT, A CORPORATION OF CONNECTICUT.

CLASP OR BUCKLE.

No. 804,893.

Specification of Letters Patent.

Patented Nov. 21, 1905.

Application filed July 1, 1905. Serial No. 267,839.

To all whom it may concern:

Be it known that I, CLARENCE E. SMITH, a citizen of the United States, residing at New Britain, county of Hartford, State of Connecticut, have invented certain new and useful Improvements in Clasps or Buckles, of which the following is a full, clear, and exact description.

My invention relates to improvements in clasps, and has particular value as a fastener for belts, blankets, and like articles.

It is my purpose to provide a structure which is essentially an improvement upon the clasp made the subject-matter of my former United States Letters Patent, No. 781,916, of February 7, 1905.

Among the objects are to provide means for adding greater strength to certain parts of the clasp and greater holding power to the parts when assembled and in use.

In the drawings, Figure 1 is a plan view. Fig. 2 is a side elevation. Fig. 3 is a longitudinal section.

The fastener comprises two separable members A and B. The member A is formed by casting, while the member B is preferably formed of spring-wire. These members A and B are each provided with a slot or loop at their rear ends for receiving the ends of the article to which the clasp is to be attached.

C is a hook projecting, preferably, slightly above the main body of the member A. This hook has a comparatively narrow bill and is of substantial length, extending forward along the body of the member A to form a rib-like reinforce and aliner C'. At the forward end of the member A are two ball-like enlargements E E, arranged to provide between them a contracted passage through which the shank of the member B must be passed in attaching or detaching the two members. Each side bar B³ B³ is hooked at its forward end, the ends of said hooks being in this particular instance preferably united in the same plane to engage underneath the

bill of the hook C. The side bars B³ B³ extend along each side of the reinforce and alining-rib C', thence between the ball-like enlargements E E, and thence to the loop end. In this case the free ends of the wire forming the member B are preferably at the rear and form the bar around which the strap end or other article (not shown) may be secured. If desired, a tubular lining-piece B² may be provided to cover these free ends. In this case, as in my former case, it is the flexibility of the side bars B³ B³ which permits the shank to be passed through the space between the ball-like enlargements E E. The rib-like reinforce C' gives substantially greater strength to the body of the member A. It also acts as a backing for the hook-bill. It also tends to aline the side bars B³ and guide them into the space between the ball-like enlargements E E, and it also coöperates with said enlargements in resisting twisting strains.

What I claim is—

In a clasp or buckle, in combination two coöperative detachable members, a rearwardly-projecting hook carried by one of said members, a forwardly-projecting strengthening and alining rib integral with said hook and the body of said hook-carrying member, two ball-like enlargements carried by said member forward of said hook but spaced apart therefrom and from each other and elevated above the plane of the body of said member, two hooks carried by the side bars of the other member and facing each other and arranged to engage underneath the hook-bill on the first member, the intermediate shank portion of said second member formed by said side bars being contracted and flexible and arranged to pass through the space between the ball-like enlargements on the first member.

CLARENCE E. SMITH.
